UNITED STATES PATENT OFFICE.

FRANCIS W. WALRAVEN AND CHARLES E. CALKINS, OF LAS CASCADAS, CANAL ZONE.

WATER-GAGE.

1,075,881.

Specification of Letters Patent.

Patented Oct. 14, 1913.

Application filed August 7, 1912. Serial No. 713,868.

To all whom it may concern:

Be it known that we, FRANCIS W. WALRAVEN and CHARLES E. CALKINS, citizens of the United States, residing at Las Cascadas, in the Canal Zone, have invented new and useful Improvements in Water-Gages, of which the following is a specification.

This invention relates to water gages for steam boilers, the object in view being to 10 provide a simple, cheap, and reliable device of the class described to take the place of the ordinary glass gage now in common use, and provide a perfectly reliable and safe means of visually indicating the water level 16 in steam boilers of all descriptions.

It is well understood that the ordinary water glass gages frequently burst, and on locomotives the engineers and firemen are often scalded by the hot water and steam, 20 and many have been permanently blinded by flying pieces of glass lodging in their eyes. Furthermore, water glass gages are not at all times reliable, inasmuch as they become discolored from sediment forming 25 in the glass, thereby obscuring the water level from view; this often causes a false impression as to the level of the water in the boiler, and results in a condition which may cause an explosion by reason of low water.

30 By means of the present invention, the objectionable features, hereinabove referred to, are entirely done away with, and the indicator is always in plain view, and the movement thereof varies with every change 35 of the water in the boiler. Furthermore, large openings are practical, leading to and from the boiler, and are, therefore, not liable to become obstructed by scale and pieces of packing usually employed in connection 40 with the glands of the boiler fittings of the water glass gage. After the device of this invention is installed, there is practically no expense of maintenance.

45 With the above and other objects in view, the invention consists in the construction, combination and arrangement of parts, as will be hereinafter more fully described, illustrated in the accompanying drawings, and pointed out in the claim hereunto appended.

50 In the drawings: Figure 1 is a vertical longitudinal section through a water gage, embodying the present invention. Fig. 2 is a similar view taken at right angles to Fig. 1.

The water gage of this invention com-

prises, in the preferred embodiment thereof, a vertical stand pipe or cylindrical body 1, to which are attached base and cap sections 2 and 3, respectively, each of said sections 60 being internally threaded, as shown, to receive the adjacent exteriorly threaded end of the body 1. The base 2 is provided with a central opening 4 extending downward therethrough and internally threaded to receive a blow off nozzle 5 adapted to allow any sediment to be blown off from the gage in the usual manner. The base 2 is further provided with a laterally extending exteriorly threaded nipple 6, to which the water 70 connection from the boiler may be fitted, in a manner well understood.

The upper cap section 3 is internally threaded to receive an exteriorly threaded plug 7, which is provided with a small central opening 8, through which the stem 9 of a float 10 passes, said float being of hollow construction, as illustrated in the drawings, and adapted to rise and fall in accordance with the level of the water contained in the body 1. Ordinarily the float 10 has the upper wall thereof thickened and internally threaded, as shown at 11, to receive the lower threaded extremity of the stem 9. The plug 7 is further provided at its upper side 85 with an internally threaded extension 12, into which is screwed a gland 13, beneath which suitable packing is arranged, as shown at 14, to provide a tight joint between the stem 9 to prevent the escape of steam and water from the gage. The gland 13 is further bored and threaded to receive the lower threaded extremity of a tube 15, which extends upward any suitable distance above the gage, and is provided in one side with 90 a longitudinal slot 16, in which works a small lateral extension 17 of the stem 9, as shown in Fig. 2. To the extension 17 is secured an indicator 18 which travels up and down against or adjacent to the outer 100 face of the guide tube 16, thereby visually indicating to the fireman or engineer the level of water contained in the boiler and in the gage.

From the foregoing description, it will be 105 seen that the water gage of this invention is strong and reliable, and it is impossible for the indicator to become clogged or inoperative or unreliable, for any reason whatever. Preferably, the stem 9 will be made 110 quite small, so that there will be a minimum amount of friction in the reciprocating

movements of the same back and forth through the stuffing box, the tube 15 serving as a protection for the stem 9 to prevent the same from becoming broken, bent, or otherwise injured, when the float is in an elevated position.

What is claimed is:

A water gage for steam boilers, comprising a cylindrical body, base and cap sections 10 having a threaded connection therewith and provided respectively with water and steam ports, a blow-off nozzle leading outwardly from the base section, a tubular casing extending upwardly from the cap section and 15 provided with a longitudinal slot, a float

in the cylindrical body movable back and forth between the steam and water ports, a stem extending from the float upwardly within said tube and having a laterally extending extremity movable in said slot, and 20 a sight indicator carried by the laterally extending extremity of said stem and movable along the outer face of said tube.

In testimony whereof we affix our signatures in presence of two witnesses.

FRANCIS W. WALRAVEN.

CHARLES E. CALKINS.
